UNITED STATES PATENT OFFICE.

LAURENCE VINCENT BENÉT AND HENRI ALBERT MERCIÉ, OF PARIS, FRANCE.

CARTRIDGE-CASE EXTRACTOR.

1,041,410.

Specification of Letters Patent.

Patented Oct. 15, 1912.

Application filed March 19, 1912. Serial No. 684,895.

To all whom it may concern:

Be it known that we, LAURENCE VINCENT BENÉT and HENRI ALBERT MERCIÉ, citizens of the United States and France, respectively, residing in Paris, in the Republic of France, have invented certain new and useful Improvements in Cartridge-Case Extractors; and we do hereby declare the following to be a full, clear, and exact description of the invention, such as will enable others skilled in the art to which it appertains to make and use the same.

Our present invention relates to improvements in apparatus for positively and efficiently extracting the empty cartridge case after the piece has been fired, and for ejecting the same laterally from the piece. It is especially adapted for use in breech-loading small arms or machine guns, in which the breech block has a rectilinear movement in the receiver.

The object of this invention is to provide for use in arms of the classes specified, and others, an extractor which will with certainty extract spent cartridge cases from the chamber of the firearm, that it may be readily and cheaply manufactured, and that it may be assembled and dismounted from the breech block of the arm with facility, without previously dismounting the breech block or other component parts of the mechanism.

In the annexed drawings, the extractor is shown as applied to the breech block of the Benét-Mercié automatic machine rifle, subject of United States Patent No. 861,939, issued July 30, 1907, and entitled Gas operated guns.

Figure 1 shows a central horizontal section through the barrel, the breech block, and receiver, parts being shown in plan, and the breech block being shown in the closed, and the firing pin in the forward position, the parts of the apparatus not essential to the description of the invention being omitted, for the sake of clearness in the drawings. Fig. 2 is a similar view, showing the breech block about midway of its forward movement, and the firing pin in the withdrawn or cocked position. Fig. 3 shows a central horizontal section through the forward end of the breech block, as seen from beneath, and shows the emplacement of the improved extractor. Fig. 4 is a side elevation of the forward end of the breech block, as seen from the left of Figs.

1 and 2, and as seen from the top of Fig. 3. Fig. 5 is a front elevation of the breech block. Fig. 6 shows a section through the breech block, along the line 6—6 of Fig. 3, 60 and looking in the direction of the arrows. Fig. 7 is an inverted plan view of the extractor, parts being broken away. Fig. 8 is a side elevation of the extractor as detached. Fig. 9 is a front view of the extractor, and Fig. 10 shows a section across the body of the extractor, along the line 10—10 of Fig. 7.

Referring to the parts generally, A represents the receiver, in which the breech 70 mechanism and barrel are mounted; B represents the barrel; C represents the fermeture nut; D represents the breech block; E the extractor; G the extractor spring; and H the ejector. The fermeture nut C 75 has interrupted screw-threads c, adapted to engage the interrupted screw-threads d on the reciprocating breech block; and this fermeture nut is turned in the manner described in our patent aforesaid. The means 80 for reciprocating the breech block, for rotating the fermeture nut, and for operating the firing pin, not being a part of our present invention, will not be further described.

The breech block D is provided at one 85 side with a longitudinal slot d¹, to receive the inwardly projecting ejector, and on the opposite side is provided with a recess d', forming an emplacement for the extractor. This recess is open to one side of the breech 90 block, as shown most clearly in Figs. 2 and 4. The recess d' is enlarged as at d², to receive the extractor spring G, and in rear of the enlargement d² there is, preferably a small indentation d³, into which fits loosely 95 the tail end e³ of the extractor. The extractor is provided with a shoulder e², to form an annular bearing for the extractor spring G, which normally tends to push the extractor forward, as will be hereinafter described. This extractor spring G projects into the recess at the rear end of the spring chamber d², which is only partly closed by the overhanging lips d⁴, as shown most clearly in Figs. 2, 4, and 6. These overhanging lips hold the spring against dropping out, and yet permit access to the rear coils of the spring, to facilitate the dismounting of the extractor, as will be herein- 105 after described.

On the front of the breech block is formed a protuberance D', through which is worked

a passage d^0 , adapted to receive the forward end of the extractor. At the outer side of this passage, there is a plane face d^4 , adapted to engage the plane face e^4 of the extractor head opposite the claw e . In rear of this, there is an inclined or wedge face d^5 , adapted to engage the wedge face e^5 of the extractor. For convenience of manipulation, and to insure lightness, the body portion of the extractor is cut away, as at e^6 .

It will be noted that the emplacement for the extractor is open laterally through the major portion of its length, as shown most clearly in Figs. 2 and 4.

15 On the opposite side of the breech block from the recess for the extractor, is the groove d^7 , into which projects the shouldered end h of the ejector H , which is preferably in the form of a spring plunger, 20 whose stem h' projects through the hollow sleeve I , screwed into the bushing K . The ejector H is normally thrust inwardly by the spring L .

25 The action of the extracting and ejecting mechanism is as follows:—In the Benét-Mercié automatic machine rifle (as described in U. S. Patent No. 861,939 aforesaid), to which it is shown as applied by way of illustration, the breech block has 30 rectilinear motion only when opening and closing the breech. In the forward motion of the breech block, the latter pushes a cartridge previously held in a loading clip or packet of well known construction, from 35 said clip or packet into the chamber of the barrel. The inclined front surface of the extractor claw strikes the head of the cartridge, causing the extractor to be pushed to the rear, and compressing the extractor 40 spring G , the extractor claw being wedged away from the axis of the gun until the claw can pass over the rim of the cartridge, or over the head in the case of a cannelured cartridge. Once the claw 45 passes over the head of the cartridge or in line of the cannelure, the extractor spring forces the extractor to the front, bringing the claw in line with the cannelure, or to the front of the cartridge rim. The 50 wedge face d^5 , acting against the wedge face e^5 , causes the extractor, under the influence of the spring, fully to engage with the cannelure, or in front of the rim of the cartridge case, as shown in Fig. 1. On the dis- 55 charge of the gun, the breech block is re-tracted in the usual way, as by hand, or in the present case by the gas operated motor piston, fully described in our patent aforesaid. In its rearward motion, the resistance 60 of the cartridge case aids the extractor spring, by further exerting a longitudinal forward stress upon the extractor, and through the action of the wedge faces d^5 and e^5 tends further to force the extractor 65 claw toward the longitudinal axis of the car-

tridge case. The cartridge case, being held against such motion by the usual projection on the face of the breech block, is tightly and positively gripped between said projection and the extractor claw. Thus, 70 it will be seen that the greater the resistance of the cartridge case to extraction, the more firmly will the extractor grip the cartridge case.

75 During extraction, the extractor is firmly held as follows:—The extractor claw e , through the resistance of the cartridge case, tends to draw the extractor toward the front of the breech block. The extractor, therefore, bears, first through its claw upon 80 the cartridge case itself. The second bearing is between the two inclined planes d^5 and e^5 , and by reaction there is further bearing of the annular guide e^2 against the inner wall of the recess d' on the breech block. 85 The breech block continuing its rearward motion extracts the cartridge from the chamber, and holds it positively until the head of the cartridge strikes the ejector H , when through its own momentum it is ejected to the left through the ejection opening in the receiver of the gun.

90 Through the above construction, the shock produced by the violent contact between the head of the cartridge and the ejector has no 95 destructive effect upon the extractor claw, for the reason that when struck by the ejector the cartridge case pivots about that portion of its head lying between the extractor claw and the face of the breech 100 block, and striking the wedge front face of the extractor claw, causes the extractor to move slightly toward the rear, thereby relieving the pressure between the inclined surfaces d^5 and e^5 .

105 To dismount the extractor from the gun, the breech may be opened, when the extractor will be exposed through the ejection opening in the receiver of the gun. A spent cartridge case may then be engaged between 110 the last two spirals to the rear of the extractor spring. This may be compressed to the front and disengaged from beneath the lips d^0 in the breech block. The tail e^3 of the extractor may now be pivoted outward, 115 and the extractor withdrawn.

120 To remount the extractor, the extractor spring is first slid over the extractor tail. The extractor claw is passed through the passage d^0 until brought up through contact of the wedge face e^5 with the wedge face d^5 . The extractor spring is now compressed by means of inserting the head of a spent cartridge case between the two last 125 spirals of the extractor spring, when the extractor spring and tail of the extractor may be swung inward until the former engages in the recess beneath the lips d^0 .

130 While the above description applies to an extractor mounted on breech block having

only motion of translation, it is evident that it may equally well be applied to breech blocks having motion first of rotation and then of translation. It will also be obvious 5 that various modifications might be made in the location of the extractor, and in the construction, combination, and arrangement of the various parts, which could be used without departing from the spirit of our invention.

Having thus described our invention, what we claim and desire to secure by Letters Patent of the United States is:—

1. In a magazine fire-arm, the combination of a reciprocating breech block provided with a laterally open recess for the extractor, through which the extractor may be readily removed, and with a transverse shoulder closing the forward portion of the lateral recess, said shoulder having a wedge face projecting into said extractor recess, an extractor mounted in said extractor recess and provided with a wedge face engaging said wedge face on the breech block, 25 and with a claw oppositely disposed to said wedge face, and a coil-shaped extractor spring also mounted in said laterally open recess and normally pressing said extractor toward said wedge face on the breech block, 30 substantially as described.

2. In a magazine fire-arm, the combination of a reciprocating breech block provided with a laterally open recess for the extractor, through which the extractor may be readily removed, and with a transverse shoulder closing the forward portion of the lateral recess, said shoulder having a wedge face projecting into said extractor recess, an extractor mounted in said extractor recess 40 and provided with a wedge face engaging said wedge face on the breech block, and with a claw oppositely disposed to said wedge face, and with a reduced tail, and a coil-shaped extractor spring inclosing said tail, said spring being also mounted in said laterally open recess and normally pressing 45 said extractor toward said wedge face on the breech block, substantially as described.

3. In a magazine fire-arm, the combina-

tion of a reciprocating breech block provided with an ejector groove in one side thereof, and a laterally open recess for the extractor in the opposite side, through which the extractor may be readily removed, said breech block being also provided with a transverse shoulder closing the forward portion of the lateral recess, said shoulder having a wedge face projecting into said extractor recess, a spring impressed ejector projecting into said ejector groove, an extractor mounted in said extractor recess and provided with a wedge face engaging said wedge face on the breech block, and with a claw oppositely disposed to said wedge face, and a coil-shaped extractor spring also mounted in said laterally open recess and surrounding the heel of said extractor and normally pressing said extractor toward said wedge face, substantially as described.

4. In a magazine fire-arm, the combination of a reciprocating breech block provided with an ejector groove in one side thereof and with a laterally open recess for the extractor in the opposite side, through which the extractor may be readily removed, and a transverse shoulder closing the forward portion of the lateral recess, said shoulder having a wedge face projecting into said extractor recess, an ejector projecting into said ejector groove, an extractor mounted in said extractor recess and provided with a wedge face engaging said wedge face on the breech block, and with a claw oppositely disposed to said wedge face, and with a reduced tail, and a coil-shaped extractor spring also mounted in said laterally open recess and inclosing said tail, and normally pressing said extractor toward said wedge face on the breech block, substantially as described.

In testimony whereof, we affix our signatures, in presence of two witnesses.
